UNITED STATES PATENT OFFICE.

SAMUEL KOFF, OF NEW YORK, N. Y.

BOX.

1,401,794.

Specification of Letters Patent. Patented Dec. 27, 1921.

Application filed December 31, 1920. Serial No. 434,341.

To all whom it may concern:

Be it known that I, SAMUEL KOFF, a citizen of the United States, residing at New York, in the county of New York and State 5 of New York, have invented certain new and useful Improvements in Boxes; and I do hereby declare the following to be a full, clear, and exact description of the invention, such as will enable others skilled in the art 10 to which it appertains to make and use the same.

The present invention relates to boxes made of paper or fiber board and aims to provide a box of novel and improved construction adapted especially for shipping clothes or wearing apparel, without the need 15 of wrapping the box in paper, as usual.

One of the objects of the invention is the provision of a box comprising tray-like bottom and top sections to telescope or fit together one on the other, and such sections each being formed from a blank and having 20 secure corner constructions.

A further object is the provision of novel 25 means carried by the inner or bottom section for preventing access into the box between the margins of the top sections for the purpose of withdrawing garments, or the like, from the box, without detection.

As a more specific object, in this connection, the invention aims to provide flaps at 30 the edges of the inner or bottom section to overlie the contents and to prevent a person from reaching into the box and pulling out 35 the garments or similar articles without detection, when the box is tied or bound for shipment.

A still further object is the provision of 40 novel means for the engagement of such flaps with one another in overlapping relation to retain them in place, and render access into the box more difficult, without opening the box.

With the foregoing and other objects in 45 view, which will be more apparent as the description proceeds, the invention resides in the construction and arrangement of parts hereinafter described and claimed, it being understood that changes can be made within 50 the scope of what is claimed without departing from the spirit of the invention.

The invention is illustrated in the accompanying drawing, wherein:—

Figure 1 is a perspective view of the bottom 55 section or body of the box.

Fig. 2 is a similar view of the top section or cover.

Fig. 3 is a plan view of the bottom section in blank, prior to folding thereof into shape.

The box is of flat form, such as used for 60 the transportation of cloaks, suits, dresses, furs and other garments or wearing apparel, and the like, and the box is of elongated or rectangular form, as shown. The box is composed of two tray-like sections to telescope 65 or fit one on the other, and each section is formed from a blank of paper or fiber board of suitable quality to resist breakage of the box during handling and shipment.

The bottom or inner section comprises the 70 bottom 7 and the side walls 8 and end walls 9 bent upwardly from the bottom, and said walls are provided at the ends thereof with the triangular securing flaps 10 and 11, respectively. The flaps 10 of the side walls 75 overlap the end walls on the exterior, whereas the flaps 11 of the end walls overlap the side walls on the interior, and such flaps are secured to such walls by means of staples 12, or the like, engaging inwardly through such 80 walls and flaps to prevent them from being torn apart without detection. All of the flaps 10 and 11 have edges coinciding with the edges of the side and end walls, respectively, and staples or securing elements 12 85 preferably extend along the diagonal edges of the flaps which extend from the edges of the body or section of the box to the corners thereof, thereby providing secure corner constructions that will withstand rough handling and tampering.

The outer section or cover 13 is of the same construction as above described, but slightly larger to telescope or fit over the bottom section or body.

The bottom or inner section is, in addition to the foregoing construction, provided with means for preventing the insertion of a hand and the withdrawal of a garment or similar article from the box without detection, when 100 the box is tied or bound for transportation. The side walls 8 and end walls 9 have the respective flaps 14 and 15 extending from the edges thereof, and such flaps can be folded over the contents after same are 105 placed in the box. The end flaps 15, as shown, can be folded over the end portions of the side flaps 14 so that the flaps overlap at their ends. Such flaps will therefore make it impossible for a person to reach into 110

the box between the body and cover to withdraw a garment or other object from the box without so tearing or mutilating the box that same can be readily detected and 5 the guilty person in charge of the shipment held responsible.

The guard flaps 14 and 15 have means whereby they can engage one another, to hold them in place, and thereby make access 10 into the box more difficult. Thus, the side flaps 14, which are lowermost of the said flaps, are provided with diagonal slits 16 extending from their edges at suitable points, and providing pointed tabs 17 which are so 15 arranged, that when the flaps 15 are folded down over the flaps 14, said tabs 17 can be sprung over the edge portions of the flaps 15, as seen in Fig. 1, thereby holding the flaps 14 and 15 down in place after the contents 20 have been placed within the body of the box, and to prevent such flaps raising while putting the cover on. Furthermore, the flaps being thus engaged with one another will make it impossible to separate 25 them, without detection, for purpose of removing part of the contents from between the two sections without opening or mutilating the box.

The present box is especially desirable for 30 the shipment of clothes, garments, and the like without the necessity of inclosing the box in wrapping paper, as customary.

Having thus described the invention, what is claimed as new is:—

1. A tray-like box section having flaps extending from its walls to overlap one another and overlie the contents, some of said flaps being slit obliquely from those edges opposite to the corresponding walls to engage the edges of the others for holding said flaps in overlapping relation. 35

2. A tray-like box section having flaps extending from its walls to overlap one another and overlie the contents, some of said flaps having tabs at those edges opposite to 45 the corresponding walls and spaced from the ends of such flaps to be snapped over the edges of the other flaps for holding the flaps in overlapping relation.

3. A tray-like box section having flaps extending from its walls to overlap one another and overlie the contents, some of said flaps having slits extending from the edges thereof opposite to the corresponding walls and forming tabs to be snapped over the 55 edges of the other flaps for holding the flaps in overlapping relation.

In testimony whereof I have signed my name to this specification in the presence of two subscribing witnesses.

SAMUEL KOFF.
